UNITED STATES PATENT OFFICE.

JÖRGEN TVEDE MYGIND, OF COPENHAGEN, DENMARK.

PHONOGRAPH-REPRODUCER.

No. 887,833.

Specification of Letters Patent.

Patented May 19, 1908.

Application filed June 4, 1907. Serial No. 377,233.

To all whom it may concern:

Be it known that I, JÖRGEN TVEDE MYGIND, polytechnician, subject of Denmark, residing at Gl. Kongevej No. 138, Copenhagen, Denmark, have invented new and useful Improvements in Phonograph-Reproducers, of which the following is a specification.

The object of the present invention is to 10 make the connection between pin and sounding membrane of the reproducing-part of Edison's and similar phonographs specially light and of easy movement as well as free from secondary sounds, thereby obtaining a 15 more delicate and purer reproduction than when using the usual reproducers of this kind.

The principal feature of the invention consists in the lever which carries the pin, and 20 which is connected to the membrane through a link, being arranged in such a manner that its three points of engagement, viz: the point of contact between the pin and the cylinder, the point of action of the connecting link, and finally the fixed fulcrum of the lever, situated between these two movable points, lie as far as possible in a straight line.

According to the well-known laws of the 30 lever, the aforesaid arrangement affords the most favorable conditions for an easy movement, and consequently a more delicate reproduction may be obtained than by means of the usual form of the lever, in which the three points in question form the 35 corners of a triangle. Besides this, the invention provides for a suitable suspension of the lever and a certain amount of damping of the connecting-link, so that the formation of secondary sounds at these places 40 is avoided.

The invention is illustrated on the accompanying drawing, in which

Figure 1. shows a section through the reproducer, Fig. 2 a cross section of the lever 45 through the suspension in the fulcrum, Fig. 3. the placing of the three points of engagement of the lever on a straight line, and Figs. 4 and 5 each a form of the connecting link.

50 a Fig. 1, is a membrane of copper or other suitable material the edge of which is by means of the screw-threaded clamping ring *b* firmly wedged in between soft disks *c* of india-rubber, paper or the like.

55 *d* is the external casing to which the funnel (not shown) is fitted, and which by means of

a hinge *e* supports the usual plate-piece *f*, the top of which is bent back. The natural propensity of this to clap down is counteracted for example by a lug *g* fitted onto the casing, 60 engaging a pin *h*.

A fork piece *i* (see Fig. 1) or two separate pieces *j* (see Fig. 2) with bearings serve as suspension means for the lever *k*, which is, through the piece *l*, connected to the center of the membrane, and at its opposite end 65 said lever carries the pin *m* which slides on the cylinder *n*.

As mentioned above, and as indicated in Fig. 3 the three points of engagement are placed as nearly as possible on a straight line. 70 Hereby is also attained the possibility of materially decreasing the bulk of the lever.

In order to effect a certain amount of damping on the connecting link *l* so as to avoid deleterious independent motion, it is 75 provided with a lump *o* of sealing wax or shellac or the like fused onto it.

For the same reason instead of the usual suspension of the lever by means of a screw the suspension means as shown in Fig. 2 is 80 used, which consists in a piece of wire *p*, bent to the shape of a crank, which is held in place by its own tension.

Having now particularly described and ascertained the nature of this said invention 85 and in what manner the same is to be performed I declare that what I claim is:

1. A reproducing device for phonographs comprising a casing, a membrane therein, a forked member on the casing having openings therein, a lever, a pin carried by one end of the lever, a link connecting the other end to the membrane, and a wire bent as a crank on which the lever is carried, the ends of said wire passing through the openings in the 90 forked member, and being held in place by its own tension.

2. A reproducing device for phonographs comprising a casing, a membrane therein having an eye-bolt thereon, a lever pivoted 100 on the casing, a pin carried by one end of the lever and a bent wire connecting the other end of the lever to the eye bolt on the membrane, and a mass fused into the bent wire.

In testimony whereof I have signed my 105 name to this specification in the presence of two subscribing witnesses.

JÖRGEN TVEDE MYGIND.
